UNITED STATES PATENT OFFICE.

HORACE E. WELLS, OF CLEVELAND, OHIO.

DISINFECTING WATER-CLOSETS.

SPECIFICATION forming part of Letters Patent No. 276,106, dated April 17, 1883.

Application filed October 26, 1882. (No model.)

To all whom it may concern:

Be it known that I, HORACE E. WELLS, of Cleveland, in the county of Cuyahoga and State of Ohio, have invented certain new and useful Improvements in Disinfecting Water-Closets; and I do hereby declare the following to be a full, clear, and exact description of the invention, such as will enable others skilled in the art to which it pertains to make and use to the same.

My invention relates to mechanism for distributing disinfectants or deodorants, or both, and also for measuring liquids when so desired; and it consists of parts and combinations of parts, as will be more fully hereinafter described and claimed.

In the drawings is shown my invention as applied to water-closets, and also as applied to measuring liquids, although the same mechanism is applicable to other purposes and to other places where it is desired to use liquid disinfectants or deodorants.

Figure 1 is a front elevation of one embodiment of my invention, showing also a vertical 25 sectional view of the bowl and other fixtures of a water-closet. Fig. 2 is a view in vertical section of the device shown in Fig. 1. Fig. 3 is an enlarged vertical section of one part of the device shown in Fig. 1.

In the drawings, A A represent a case, of any desired material or construction, with the front part removed, in which the mechanism may be placed.

B is a containing-tank for storing liquid disinfectants or deodorants suitable for use in the soil-bowls of water-closets.

C is a vertical cylinder or well connected with tank B, and provided with an orifice or orifices, R R R, leading from the tank B, through which the liquid may flow to the well C. The well C may be provided with a spout or equivalent discharging-outlet, D. The well C has a loose-fitting plunger, G, attached by the rod or connection H to the lever I I. The lever I I is fulcrumed at J, and has attached at one end the weight L. The other end of the lever I I is connected by the chain M M and the bell-crank N to O, the cover of the water-closet. The attachment of the chain M M to the cover O is made a short distance from the hinges of the cover O.

The operation of the device is as follows:

When the cover O is shut down the end of the lever I I that is attached to the cover O by the chain M M and the bell-crank N is drawn down. 55 When the cover O is raised the chain M M is loosened, and the end of the lever I I to which the weight L is attached is drawn down by the gravity of the weight L. This operation of the lever I I by means of the connection H 60 alternately raises and lowers the plunger G. When the plunger G is thus raised out of the well C the liquid in the tank B flows by its own gravity into the well C, bubbles of air passing at the same time back into the tank 65 through orifices R R R, taking the place of the receding liquid. When the liquid has risen in the well until the orifices are covered no more air can then pass into the tank. Consequently no more liquid can flow from the tank 70 without causing a partial vacuum, which, of course the atmospheric pressure would prevent. When the plunger G descends into the well C it displaces a portion of the liquid 75 into the outlet D.

When it is desired to use two kinds of liquids—the one kind suitable for disinfecting the soil-bowls of water-closets and the other liquid suitable for disinfecting or deodorizing 80 the air in the room—then in that case two tanks are used, and the one tank may be placed above the other. In such case both tanks are provided with a well, C, a spout, D, a plunger, G, and attachments, as heretofore described. 85 In such case the spout D of the lower well terminates in the pipe P, which conveys the liquid to the bowl of the water-closet Q, and the spout D of the upper well discharges the liquid 90 upon an apron, S, made of cloth or other suitable material, when the said liquid is left to evaporate and disinfect or deodorize the room.

When it is desired to use the apparatus for measuring liquids from the tank the plunger G should be made of such a size as to displace 95 a given quantity of liquid—such, for example, as one ounce; and in place of the attachment M M the lever I I may be worked by the handle F.

A graduating-scale, U, may be used in combination with the handle F and lever I I. The lever I I being connected to the plunger G by the attachment H, as aforesaid, it follows that 100 graduating the stroke of the lever will also

graduate the stroke of the plunger, so that any measure of liquid desired may be displaced by a stroke of the plunger G, provided that said desired measure be less than the full displacement of the plunger.

5. What I claim is—

1. The combination, with the supply-tank, of a well situated alongside of the said tank and in communication therewith by orifices, which 10 latter control the amount of liquid passing into the well, and a plunger for forcing the liquid from the well by displacement.

2. The combination, with the supply-tank and a well secured to the side of the said tank 15 and in communication therewith by a series of orifices, of a plunger for displacing the liquid in the well, the connecting-rod H, weighted lever I, and connecting mechanism for moving the plunger simultaneously with the lid of 20 the closet, substantially as set forth.

3. The combination, with the supply-tank, the well secured thereto and in communication therewith by suitably-arranged orifices, whereby the flow of liquid from the supply-tank is 25 controlled, and a plunger adapted to displace the liquid in the well, of the lever I, weight L, connecting-rod H, connecting mechanism M,

bell-crank N, and the closet-cover O, all of the above parts constructed and adapted to operate as described.

30

4. The combination, with the supply-tank and a well situated alongside the same and in communication therewith by suitably-arranged orifices, of a measuring-plunger adapted to move in the said well and discharge the contained liquid by displacement, the connecting-rod H, the lever I, and the graduated scale U, all of the above parts combined and adapted to operate as described.

35

5. The combination, with devices for supplying a water-closet bowl with disinfectant, of a supply-tank, a well situated alongside of the same and in communication therewith, a plunger for displacing the liquid in the well, and an apron on which the disinfectant falls, 40 substantially as set forth.

45

In testimony whereof I sign this specification, in the presence of two witnesses, this 19th day of October, 1882.

HORACE E. WELLS.
